UNITED STATES PATENT OFFICE.

FREMONT STOKES, OF CLARKSVILLE, ARKANSAS.

CONNECTING-ROD FOR INTERNAL-COMBUSTION ENGINES.

1,331,881.

Specification of Letters Patent. Patented Feb. 24, 1920.

Application filed February 10, 1919. Serial No. 275,951.

To all whom it may concern:

Be it known that I, FREMONT STOKES, a citizen of the United States, residing at Clarksville, in the county of Johnson and State of Arkansas, have invented certain new and useful Improvements in Connecting-Rods for Internal-Combustion Engines, of which the following is a specification, reference being had to the accompanying drawings.

This invention relates to certain improvements in connecting rods and has relation more particularly to a device of this general character especially designed and adapted for use in connection with a piston and crank shaft of an internal combustion engine, and it is an object of the invention to provide a rod of this type having novel and improved means whereby the same may be adjusted longitudinally in order to effect an adjustable combustion chamber and particularly to regulate or control compression.

Another object of the invention is to provide a novel and improved connecting rod comprising two relatively movable sections or members adjustable one longitudinally of the other so that the coacting piston may be variably set relative to the crank in order to obtain the best results and especially as relates to compression.

An additional object of the invention is to provide a novel and improved connecting rod of this general type embodying two longitudinally adjustable sections together with novel and improved means whereby the sections are locked in their different adjusted positions.

The invention consists in the details of construction and in the combination and arrangement of the several parts of my improved connecting rod whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood I will now proceed to describe the same with reference to the accompanying drawings, wherein:

Figure 1 is a view partly in elevation and partly in section illustrating a connecting rod constructed in accordance with an em-

bodiment of my invention, the coacting piston being indicated by dotted lines;

Fig. 2 is a fragmentary longitudinal sectional view taken through the connected end portions of the sections of the rod and on a line substantially at right angles to the line of section in Fig. 1, the locking members being shown in elevation; and

Fig. 3 is a sectional view taken substantially on the line 3—3 of Fig. 2.

As disclosed in the accompanying drawings, C denotes a connecting rod in its entirety constructed in accordance with an embodiment of my invention, and which comprises two sections 1 and 2. The outer end portion of the section 1 is engaged, as at 3, in a conventional manner with the piston P while the outer end portion of the section 2 is also engaged, as at 4, in a conventional manner with the crank shaft S.

The inner end portion of the section 2 at its axial center is provided with an internally threaded socket 5, with which is engaged the peripherally threaded inner end portion 6 of the section 1. It will be obvious that upon rotation of the sections 1 and 2 one relative to the other, the rod C may be lengthened or shortened as the occasions of practice may demand and which results in the desired spacing of the piston P relative to the crank shaft S so that the combustion chamber of the cylinder in which the piston P operates may be also adjusted. As herein disclosed and as preferred the socket 9 is produced by disposing through the section 2 a slot, said slot intersecting the inner end portion of the socket 5 and extending inwardly thereof. The slot is also of a width to permit unobstructed rotation of the section 1 and the member 2, one with respect to the other. This adjustment of the combustion chamber is particularly advantageous in the regulation of compression as is believed to be clearly obvious to those skilled in the art to which my present invention appertains.

The inner end portion of the section 1 of the rod C at its axial center is provided with a bore or socket 7 angular in cross section and snugly and slidably engaged within said bore or socket 7 is a rod 8. The outer end of the rod 8 seats within a supplemental socket 9 arranged at the base of the socket or bore 5 and in which the rod 8 extends.

Removably disposed transversely through

the section 2 and passing through the rod 8 is a pin or key 10 whereby the rod 8 operates to hold the sections 1 and 2 against relative rotation so that a desired seating 5 or adjustment of the sections 1 and 2 longitudinally is maintained. The rod 8 is of a length to contact with the base of the supplemental socket 9 and normally contacts therewith by gravity, so that the application 10 of the pin 10 is materially facilitated as the opening in the rod 8 through which the pin 10 is directed is made in proper alignment with the openings on the section 2 through which said pin 10 is disposed.

15 When it is desired to adjust the sections 1 and 2 in a direction one longitudinally of the other, it is only necessary that said sections be relatively rotated and as the threads of the bore 5 are adapted in practice to be 20 sixteen to the inch, it will be at once obvious that the sections 1 and 2 may be locked in different longitudinal adjustments of substantially one thirty-second of an inch or one-half thread.

25 From the foregoing description, it is thought to be obvious that a connecting rod constructed in accordance with my invention is particularly well adapted for use by reason of the convenience and facility with 30 which it may be assembled and operated, and it will also be obvious that my invention is susceptible of some change and modification without departing from the principles and spirit thereof, and for this reason 35 I do not wish to be understood as limiting myself to the precise arrangement and formation of the several parts herein shown in carrying out my invention in practice except as hereinafter claimed.

40 I claim:—

1. In combination, a member provided with a threaded socket and with a supplemental socket in connection with and positioned inwardly of the first named socket, a 45 member having threaded engagement within the first named socket, the inserted end portion of the second member being provided with a bore angular in cross section, a rod snugly and slidably engaged within the bore of the second member and of a length 50 to extend within the supplemental socket, said rod normally engaging by gravity the bottom of the supplemental socket, and a removable pin disposed through the first 55 named member and through the portion of the rod within said supplemental socket.

2. In combination, a member provided with a threaded socket and with a supple-

mental socket in connection with and positioned inwardly of the first named socket, a 60 member having threaded engagement within the first named socket, the inserted end portion of the second member being provided with a bore angular in cross section, a rod 65 snugly and slidably engaged within the bore of the second member and of a length to extend within the supplemental socket, said rod normally engaging by gravity the bottom of the supplemental socket, and a removable pin disposed through the first 70 named member and through the portion of the rod within said supplemental socket, the supplemental socket being of a diameter to permit unobstructed rotation of each of the members with respect to the other when the 75 key is removed.

3. In combination, a member provided with a socket and having a slot disposed therethrough, said slot intersecting the inner end portion of the socket and extending 80 inwardly thereof, a second member engaged within the socket and provided at its inserted end with a bore angular in cross section, a rod 85 snugly and slidably engaged within the bore of the second member and of a length to extend within a portion of the slot inwardly of the socket in the first named member and normally engaging by gravity the inner end of the slot, and a removable key disposed through the first 90 named member and the rod at a point inwardly of the socket.

4. In combination, a member provided with a socket and having a slot disposed therethrough, said slot intersecting the inner end portion of the socket and extending 95 inwardly thereof, a second member engaged within the socket and provided at its inserted end with a bore angular in cross section, a rod 100 snugly and slidably engaged within the bore of the second member and of a length to extend within a portion of the slot inwardly of the socket in the first named member, and a removable key disposed through the first named member and the rod at a point inwardly of the socket, the slot being of a width to permit unobstructed rotation of one of the members with 105 respect to the other when the key is removed.

110 In testimony whereof I hereunto affix my signature in the presence of two witnesses:

FREMONT STOKES.

Witnesses:

ROBERT A. BOSWELL,
W. E. LAWSON.
